2 SHEETS—SHEET 1.

UNITED STATES PATENT OFFICE.

JOHN WILLIAM CRAIN, OF WINCHESTER, KENTUCKY.

HEMP-BRAKE.

1,213,750.

Specification of Letters Patent. Patented Jan. 23, 1917.

Application filed March 20, 1916. Serial No. 85,452.

To all whom it may concern:

Be it known that I, JOHN WILLIAM CRAIN, a citizen of the United States, residing at Winchester, in the county of Clark and State of Kentucky, have invented certain new and useful Improvements in Hemp-Brakes; and I do declare the following to be a full, clear, and exact description of the invention, such as will enable others skilled in the art to which it appertains to make and use the same.

My present invention relates to improvements in hemp brakes in which a carriage supporting one or more movable knives is mounted in conjunction with stationary knives on a frame to be shifted back and forth to move the shiftable knives into and out of engagement with the fixed knives.

Broadly stated, the practical embodiment of the present invention, which I have operated successfully for some time, consists in a double series of spaced inverted U-shaped knives fixedly mounted on a wheeled frame for speedy and convenient transportation of the brake, and having inclined upper portions coöperating with similarly inclined portions on a series of intermediate movable knives supported on a reciprocating carriage to be moved back and forth through an automatic mechanism, to bring such intermediate shiftable knives alternately between the stationary knives of each of the double series and to thereby operate upon the hemp stalks which are thrown in bunches between the knives, they being guided by the inclined portions down between the same. I am aware that machines of a similar character have been proposed, but, as far as I know, their operation has not been attended with success.

It is accordingly the primary object of the present invention to provide a machine of the general character stated, the constructional parts of which will be simple and capable of ready assembly on the machine; and such as, when assembled, will provide an inexpensive hemp brake which has been found in practice to separate the herds or stalks from the fiber or lint of the hemp in a single operation without the necessity for intermediate processes as now done.

In the accompanying drawings forming a part of this application, and in which similar reference symbols indicate corresponding parts in the several views: Figure 1 is a fragmentary side elevational view, partly in section, of a hemp brake constructed in accordance with the present invention. Fig. 2 is a fragmentary transverse sectional view taken on the line 2—2 in Fig. 1 and Fig. 3. Fig. 3 is a fragmentary top plan view of the improved hemp brake. Fig. 4 is an enlarged plan view of the carriage. Fig. 5 is an end elevational view of the same. Fig. 6 is a transverse sectional view taken on the line 6—6 in Fig. 4 and looking in the direction of the arrows; and Fig. 7 is a diagrammatic view illustrating the hemp stalks as operated upon.

Referring more particularly to the drawings, 1 and 2 designate a pair of longitudinal channel beams connected together by angle bars 3 and 4 to constitute a frame, which is mounted for movement upon wheels 5 and 6, shown at one end only of the machine.

Supported between the angle bars 3 and 4 and attached at their ends thereto by angle irons, or other means, 7 and 8, are a series of stringers 9 upon which and upon the longitudinal channel beams 1 and 2 are mounted a double series of stationary knives 10 and 11, spaced apart, and each being preferably of the U-shaped construction more particularly illustrated in Fig. 1. The lower free ends of these stationary knives 10 and 11 are secured by rivets, or other means, 12 to the stringers 9 or longitudinal beams 1 and 2, as the case may be, and have their upper bowed portions inclined, as indicated at 13 and 14, for constituting flaring jaws for guiding and receiving the hemp stalks or other material to be operated upon. Such inclined portions 13 and 14 of the stationary knives 10 and 11 coöperate with similarly inclined portions 15 and 16 on the bowed upper ends of movable knives 17, also preferably of the U-shape construction shown in Fig. 1, and secured as by rivets, or other means, 18 and 19, each to upstanding perforated lugs 20 and 21 mounted in pairs on the heads 22 and 23 of a carriage. This carriage is constituted of the heads 22 and 23, which are preferably cast-

ings formed each with lower eyes 24 and 25, into which are received a pair of connecting rods 26 and 27. (For the construction of the carriage see more particularly Figs. 4, 5 5 and 6).

Each head 22 and 23 is also formed with an upper pair of eyes or bearings 28 and 29 for slidable mounting on a pair of tracks 30 and 31 supported in hangers 32 and 33 10 mounted on the longitudinal channel beams 1 and 2 of the framework. The head 22 is provided with a pair of perforated ears 34 and 35 between which is secured a connecting rod 36 operated from a crank shaft 37 15 to reciprocate the carriage on the tracks 30 and 31. This crank shaft 37 may be driven in any suitable manner, as, for instance, by the pulley 38 and belt 39 arrangement illustrated in Figs. 1 and 3. 20 In the operation of the improved hemp brake, supposing the parts to be in the position shown in Figs. 1 and 3, the operator will throw the hemp stalks in quantities on the machine between the series of fixed 25 knives 10 and movable knives 17, where they will be received on the inclined upper portions 13 and 15 of such knives and guided thereby downwardly between the same, the lowermost stalks resting upon the longitudinal 30 channel beams 1 and 2 and the stringers 9. The rotating crank shaft 37 will subsequently draw upon the connecting rod 36 to shift the carriage from the position shown 35 in Figs. 1 and 3 to the position indicated diagrammatically in Fig. 7, where the movable knives 17 have been brought into 40 cooperation with the stationary knives 10, between which the stalks have been described as just placed. The movable knives 17 on 45 the carriage being offset with respect to the stationary knives, will be received therebetween substantially in that manner indicated to best advantage in Fig. 7, and encountering the hemp stalks in moving to 50 this position, will effect a breaking thereof at a number of points along the stalks and substantially in the zigzag manner apparent. When in this position another charge of the hemp stalks or other material is introduced between the movable knives 17 and 55 the second set of stationary knives 11, being guided therebetween by the flaring mouths 14 and 16; and when the carriage, through the connecting rod 36 and crank shaft 37 is 60 returned to the position shown in Figs. 1 and 3, such latter mentioned stalks will be encountered and operated upon in similar manner to break the same at a variety of points in zigzag fashion. This operation is continued, the carriage supporting the movable knives 17 shifting back and forth to bring such movable knives alternately into operative engagement with the stationary 65 series of knives 10 and 11, and the hemp or

other material to be worked being alternately placed in the open spaces between the knives. When operated upon the hemp is withdrawn by the operator, and it has been found in practice that by the use of the above described machine the stalks and 70 fiber are separated without the necessity for subsequent processes.

It is obvious that those skilled in the art may vary the details of construction and arrangements of parts without departing from 75 the spirit of my invention, and therefore I do not wish to be limited to such features except as may be required by the claims.

I claim:

1. In an improved hemp brake, the combination of a framework, a double series of laterally spaced stationary knives formed each of a single strip of metal bent U-shape and inverted, the free ends of said strips being secured to said framework, the upper doubled portions of said knives being flattened and inclined, and a series of laterally spaced movable knives offset with respect to said stationary knives and adapted to be received therebetween, said movable knives also consisting each of a flat strip of metal bent U-shape and inverted and having inclined and flattened upper ends to coöperate with the inclined upper ends of the stationary knives to guide the hemp stalks 95 down to the space between said knives, substantially as described.

2. In an improved hemp brake of the character described, the combination of a wheeled frame including longitudinal and 100 transverse beams, stringers connected between said transverse beams, tracks supported from said longitudinal beams, a double series of inverted U-shaped knives having inclined portions secured to said longitudinal beams and stringers, a carriage mounted to reciprocate on said tracks between a double series of said stationary knives, inverted U-shaped movable knives mounted on said carriage and coöperating 105 with said first-named knives and having inclined portions, and means for reciprocating said carriage, substantially as described.

3. In an improved hemp brake, the combination of a framework composed of longitudinal beams, transverse beams securing said longitudinal beams together, longitudinal stringers connected between said transverse beams, a double series of laterally spaced knives consisting of strips of metal bent U-shape and inverted, the free ends of said strips being secured to the longitudinal beams and stringers, said strips having inclined upper ends, hangers mounted on said longitudinal beams, bars supported from 120 said hangers, a carriage including a pair of heads having eyes slidably received over said bars, rods connecting said heads, per-

forated ears on said heads, movable knives consisting of strips of metal bent U-shape and inverted and having their free ends secured to the perforated lugs on said heads, the upper ends of said knives being inclined to coöperate with the inclined upper ends of said stationary knives, and means for reciprocating said carriage, substantially as described.

In testimony whereof, I affix my signature.

JOHN WILLIAM CRAIN.
